Filed Mar. 8, 1971, Ser. No. 122,298

Term of patent 14 years

Int. Cl. D9—01

U.S. Cl. D9—100

FIG. 3

FIG. 1

FIG. 1 is an elevational view of a bottle embodying my new design;

FIG. 2 is an enlarged cross sectional view taken substantially along the lines 2—2 of FIG. 1; and

FIG. 3 is a bottom plan view.

The characteristic feature of my design resides in the combination on the bottle, of knurled, bulbed shoulder and heel portions connected by a recessed straight panel and a neck portion comprising two intersecting straight sections and a circumferential groove located at the point of intersection of the two sections.

I claim:

The ornamental design for a bottle, as shown and described.
